(57) **CLAIM**

The ornamental design for an egg carton, as shown and described.

DESCRIPTION

FIG. 1 is a top, front, and right side perspective view of an egg carton according to our new design;
FIG. 2 is a bottom, front, and right side perspective view thereof;

FIG. 3 is top plan view thereof;

FIG. 4 is a bottom plan view thereof;

FIG. 5 is a right side elevation view thereof;

FIG. 6 is a front elevation view thereof;

FIG. 7 is a rear elevation view thereof; and,

FIG. 8 is a left side elevation view thereof.

The broken lines represent portions of the egg carton that form no part of the claimed design.

1 Claim, 5 Drawing Sheets
